Primary Examiner — Jennifer Rivard(74) *Attorney, Agent, or Firm* — Womble Bond Dickinson (US) LLP(57) **CLAIM**

The ornamental design for a hair removal apparatus, as shown and described.

DESCRIPTION

FIG. 1 is a front perspective view of an embodiment of a hair removal apparatus of the present invention showing our new design;

FIG. 2 is a front view thereof;

FIG. 3 is a rear view thereof;

FIG. 4 is a side view thereof;

FIG. 5 is another side view rotated 180 degrees from FIG. 4;

FIG. 6 is a top plan view thereof; and,

FIG. 7 is a bottom plan view thereof.

The broken lines illustrate portions of the hair removal apparatus that form no part of the claimed design.
